J. TOMNEY.
ELECTRIC BURGLAR ALARM.

No. 289,470.

Patented Dec. 4, 1883.

UNITED STATES PATENT OFFICE.

JAMES TOMNEY, OF NEW YORK, N. Y.

ELECTRIC BURGLAR-ALARM.

SPECIFICATION forming part of Letters Patent No. 289,470, dated December 4, 1883.

Application filed February 5, 1883. (No model.)

To all whom it may concern:

Be it known that I, JAMES TOMNEY, of New York, in the county of New York and State of New York, have invented a certain new and useful Improvement in Electric Burglar-Alarms, of which the following is a specification.

This improvement relates to those electric burglar-alarms which are employed to give an alarm at an office where watch is kept of any attempt to gain access to any guarded structure.

The improvement consists in the combination, in an electric burglar-alarm, of a main circuit extending from an office to a guarded structure, means located at the office for giving an alarm there when a change occurs in the resistance of the circuit at the guarded structure, an electro-magnet and armature at the guarded structure, a main battery which is located at the office, and which is insufficient to cause the electro-magnet to attract its armature, and yet is sufficient to hold it when attracted, and means with which the armature operates to control the passage of the electric current directly from the armature to the ground. When the electric circuit is short-circuited by the opening of a window or door, the shutting of the window or door will not restore the normal circuit, for the reason that the main battery will not be able to cause the electro-magnet to attract its armature again. A prolonged alarm will therefore be given.

The improvement also consists in the combination of a main circuit extending from an office to a guarded structure, an electro-magnet at the office, an armature therefor capable of being held by the electro-magnet against it when this electro-magnet is energized by the electric current of the main battery, an electro-magnet at the guarded structure, which is incapable, when energized from the main battery, of attracting its armature, but which is capable of holding the armature when attracted, and means with which this armature operates to control the passage of the electric current directly from this armature to the ground or through a resistance-coil to the ground.

50 The improvement also consists in the com-

bination of a main circuit extending from an office to a guarded structure, a local circuit at the office, provided with means for giving an alarm, an electro-magnet at the office, an armature therefor capable of being held by the electro-magnet against it when this electro-magnet is energized by the main battery, an electro-magnet at the guarded structure, which is incapable, when energized from the main battery, of attracting its armature, but is capable of holding its armature when attracted, and means with which this armature operates to control the passage of the electric current directly from this armature to the ground or through a resistance-coil to the ground.

60 The improvement also consists in the combination of a main circuit extending from an office to a guarded structure, devices located at the guarded structure for causing an alarm to be given at the office in case an attempt is made to gain access thereto, a galvanometer at the office, and means with which the galvanometer-needle, when sufficiently deflected, will operate to short-circuit the main circuit at the office, and cause the sounding of an alarm at the office. A short-circuiting between the office and the guarded structure, accidentally or intentionally done, will deflect the galvanometer-needle sufficiently to bring about this result.

65 The improvement also consists in the combination of a main circuit extending from an office to a guarded structure, an electro-magnet located at the office, and having an armature which it is normally incapable of attracting, a galvanometer, also located at the office, and means with which the galvanometer-needle, when deflected sufficiently, operates to short-circuit the main circuit, and thereby reduce the resistance of the main circuit to such an extent that the electro-magnet will be able to attract the said armature.

70 The improvement also consists in the combination of a main circuit extending from an office to a guarded structure, an electro-magnet located at the office, and having an armature which it is normally incapable of attracting, a local circuit which can be closed by the said armature, and is provided with a device for giving an alarm, a galvanometer, also lo-

cated at the office, and means with which the galvanometer-needle, when sufficiently deflected, operates to short-circuit the main circuit, and thereby reduce the resistance of the main circuit, so that the electro-magnet can attract the said armature.

The improvement also consists in the combination of a main circuit extending from an office to a guarded structure, an electro magnet or magnets located in the office, and having armatures, one of which the electro magnet or magnets, when energized from the main battery, can attract, but not the other, while the normal circuit is maintained, a galvanometer also located at the office, and serving, when sufficiently deflected by a change of resistance, to establish a short circuit and reduce the resistance, so that the electro magnet or magnets can then attract both armatures, an electro-magnet at the guarded structure, incapable of attracting its armature, but capable of holding it when attracted, and means with which this armature operates to control the passage of the electric current directly from this armature to the ground, the resistance-coil, when introduced into the circuit, serving to so weaken the electro magnet or magnets at the office as to prevent either armature acting in conjunction therewith from being held attracted.

The improvement also consists in the combination, in an electric burglar-alarm, of a main circuit extending from an office to a guarded structure, a resistance device forming a part of the alarm apparatus and located at the guarded structure means also located at the guarded structure and serving, on the opening of a window or door of the guarded structure, to throw the said resistance device into the circuit at the guarded structure, and a device located at an office where watch is kept, and serving to give an alarm when the resistance device is thus thrown into the circuit at the guarded structure.

The accompanying drawing represents an electric burgler-alarm embodying my improvement. To conduce to a clear understanding of the same, I have drawn lines around all parts located in the office and guarded structure, and marked such lines, respectively, "Office" and "Guarded Structure." Although I have only represented one guarded structure, I will premise that any number may be connected with a single office by means similar to those shown and described.

A designates the main battery of the electric burglar-alarm. It is located in the office, one pole being connected by a wire, B, to an earth-plate, C, and the other pole by a wire, B', to one end of the coils of electro-magnets D. From the other end of the coils of the electro-magnet D a wire, B², extends to the coils of a galvanometer, E. From the coils of this galvanometer a wire, B³, extends to the metallic contact-piece *a* of a metallic switch or key, F, and from this switch a wire, B⁴, extends to the guarded structure.

A' designates a battery of greater electro-motive force than the battery A. One pole is connected by a wire, B⁵, to the earth-plate C, or to the wire B, leading thereto, and the other pole is connected by a wire, B⁶, with a metallic contact-piece, *a'*, of the switch F. Normally the switch F is in contact with the contact-piece *a*, and the electric current from the battery A passes over the electric circuit of the burglar-alarm; but under certain circumstances the switch F is shifted away from the contact-piece *a* and against the contact-piece *a'*, so as to disconnect the battery A from and connect the battery A' to the electric circuit of the burglar-alarm.

The electro-magnets D have two armatures, D' D², operating in conjunction with them. As here shown, one of these armatures is arranged at each end of the electro-magnets; but both may be arranged at the same end and in different planes, if desirable. The armature D' is retracted by a spring; but the armature D² has no means for retracting it, and, owing to the position in which it is pivoted in place, has a tendency to remain in contact with the electro-magnets after being attracted. The armatures are so combined with the electro-magnets that the armature D' will be attracted and held against the electro-magnets by an electro-motive force less than that which is necessary to cause the electro-magnets to attract the armature D². These armatures may severally close a local circuit arranged in the office. This local circuit consists of a wire, B⁵, leading from a battery, A², to a metallic switch, G, which has two metallic contact-pieces, b' b². From the contact-piece b' a wire, B⁶, extends to a contact-piece, c, with which the armature D' of the electro-magnets D makes contact when released by the electro-magnets and retracted therefrom. From the contact-piece b² a wire, B⁷, extends to a contact-piece, c', with which the armature D² of the electro-magnets D makes contact when the said electro-magnets attract it. A wire, B⁸, connected with both armatures D' D², extends thence to an electro-magnetic bell, H, and thence to the battery A². It will be readily seen that upon a certain decrease of the energy of the electro-magnets D the armature D' will be retracted, so as to close the local circuit, and that upon a certain increase of the energy of the electro-magnets the armature D² will close the local circuit, and thereafter retain it closed until retracted by hand. An alarm will be sounded by the electro-magnetic bell H in either case. Preferably this will be a continuously-ringing bell. Normally the switch G is in contact with both the contact-pieces b' b².

B⁹ designates a wire leading from the wire B³ to the pivot of the needle of the galvanometer E.

B¹⁰ designates a wire leading from a contact-piece, *d*, located near the galvanometer-needle, to the wire B⁵ or to the wire B, whereby the battery A is connected with the earth-plate C.

Under certain circumstances the galvanometer-needle is vibrated against this contact-piece d , and thereupon shunts the electric current.

5 The wire B^4 , entering the guarded structure, is connected to a metallic switch, $I I'$. This switch has two arms, $I I'$, which are connected by an insulated bar, I^2 , so as to operate in unison. The arms operate in conjunction with 10 metallic contact-pieces $e e' e^2$. The wire B^4 is connected to the arm I of the switch. When the switch is set for the night, the arm I will impinge against the contact-piece e . A wire, B^{11} , leads from the contact-piece e to the windows and doors to be protected. As here shown, it extends to one of a pair of metallic contact-pieces, f , applied to a window, J . From this contact-piece a wire, B^{12} , extends to the contact-piece e' , and as the arm I' of the 15 switch will, when the switch is set for the night, impinge against this contact-piece e' , the circuit will be continued to a fine wire, B^{13} , extending through a partition, P . Thence a wire, B^{14} , extends to the coils of electro-magnets K . Thence a wire, B^{15} , extends to a metallic circuit-breaking key, L . From this circuit-breaking key a wire, B^{16} , extends to the other of the contact-pieces f of the window J . Thence a wire, B^{17} , extends to a second fine 20 wire, B^{18} , passing through the partition P , and thence a wire, B^{19} , extends to the armature of the electro-magnets K . The armature of these electro-magnets, when attracted by the electro-magnets, impinges against a contact-piece, g' , and when retracted by its spring from the 25 electro-magnets impinges against a stop, g^2 , of insulating material. A wire, B^{20} , leads from the contact-piece g' to an earth-plate, C . A resistance-coil, M , is interposed between the 30 wires B^{19} and B^{20} . When the armature of the electro-magnets K is retracted from the contact-piece g' , the electric current from the battery passes from the wires B^{19} to the resistance-coil M , and thence along the wire B^{20} to the 35 ground. The electro-magnets K will preferably be of high resistance—say, for instance, one hundred ohms.

It will be observed that the arm I of the switch $I I'$ is provided with a projection, I^3 , 40 extending beyond its pivot. This projection is made of insulating material, and constitutes a tappet which acts upon an extension, h , of the armature of the electro-magnets K , and when the arms of the switch are adjusted to 45 the left shifts the armature so that it will impinge against the contact-piece g' .

The main battery A is not capable of energizing the electro-magnets K sufficiently to enable them to attract their armature; hence the 50 battery A' has to be switched on to enable these electro-magnets to attract their armature. When the armature is once attracted by the electro-magnets, the main battery will, however, cause the electro-magnets to hold it. 55 The contact-piece e^2 is connected by a wire, B^{22} , with the wire B^{13} .

It will be borne in mind that the switch $I I'$ is adjusted so that its arm I will impinge against the contact-piece e , and its arm I' will impinge against the contact-piece e' during 70 the night, and at other times when the inmates of the guarded structure are absent from the structure, and then the windows and doors, as well as the partitions, skylights, and other devices through which fine wiring is extended, 75 are protected. During the time that the inmates desire to use the doors and windows the switch $I I'$ is adjusted so that its arm I will impinge against the contact-piece e^2 and its arm I' will be out of contact with the contact-pieces $e e'$, and then protection is afforded to 80 the partitions and other articles through which fine wiring is run only.

I will now proceed to describe the operation of the burglar-alarm:

When the inmates of the guarded structure are about to leave it, they close all the doors and windows which are to be in circuit, and shift the switch $I I'$ so that its arm I will impinge against the contact-piece e and the arm I' will impinge against the contact-piece e' . They then signal to the watchman at the office by shifting the circuit-breaking key L , so as to break the circuit between the wires B^{15} and B^{16} . As soon as they have left the guarded 95 structure, the watchman at the office switches the battery A' onto the electric circuit for an instant, thereby causing the electro-magnets K to attract their armature to them. Afterward the main battery A causes the electro-magnets 100 to hold the armature. Normally the armature D' of the electro-magnets D will be attracted to these electro-magnets, and the armature D^2 will be out of contact with the electro-magnets. The electric current from the battery A will pass over the wire B' to the electro-magnets D , thence along the wire B^2 to the galvanometer E , thence along the wire B^3 to the switch or key F , and thence along the wire B^4 to the arm I of the switch $I I'$. From this 105 arm of the switch it passes along the wire B^{11} to one of the contact-pieces f of the window J ; thence along the wire B^{12} , the contact-piece e' , and the arm I' of the switch $I I'$, to the fine wire B^{13} of the partition P . From the wire B^{13} it passes along the wire B^{14} to the electro-magnets K ; thence along the wire B^{15} , key L , and wire B^{16} , to the other contact-piece f . Thence it passes along the wire B^{17} to the second wire, B^{18} , of the partition P . From there 110 it proceeds along the wire B^{19} to the armature of the electro-magnets K , and thence it passes along the contact-piece g' and the wire B^{20} to the earth-plate C . If the window J should be opened, the contact-pieces f would 115 be caused to impinge, and the electric current would then pass from the wire B^{11} , through these contact-pieces, to the wire B^{17} ; thence along the wire B^{18} to the wire B^{19} , the electro-magnets K being then out of the circuit. Owing to the demagnetization of these electro-magnets, their armature is retracted against 120

125

130

the stop g^2 , and the electric circuit then is broken between the armature and the contact-piece g^1 . The electric current then passes from the wire B^{19} , through the resistance-coil M, to the wire B^{20} , and thence to the ground. Even if the window were immediately closed, the circuit would remain as thus described, because the main battery A would be unable to cause the electro-magnets to attract their armature to them and restore the normal circuit. It would be just the same if the electric circuit had been broken and reunited. The resistance-coil M, when introduced into the circuit, so weakens the electro-magnets D that the armature D' thereof is retracted, closes the local circuit, and causes the electro-magnetic bell H to sound an alarm.

The position of the galvanometer - needle will indicate whether the alarm has been caused by the opening of a door, a window, or the opening of the main circuit. The normal circuit may be restored, providing the window has been closed or the break repaired at the guarded structure, by momentarily switching on the battery A'. If a short circuit should be made outside the guarded structure, even if only temporarily, the galvanometer-needle would be deflected, and, impinging against the contact-piece d , it would complete a short circuit through the wire B^{10} to the wire B^5 ; thence to the battery A; thence along the wire B', the electro-magnets D, and the wire B^2 , to the galvanometer. Owing to the resistance thus cut out of the circuit, the electro-magnets D will become energized sufficiently to attract their armature D², whereupon the local circuit will be closed and the electro magnetic bell H rung. The armature D² will be held by the electro-magnets D until released by the watchman at the office, thus producing a continuous alarm. This is a valuable feature of my improvement, as it increases the sensitiveness of the alarm. For instance, a person desirous of effecting an entrance into the guarded structure might connect the wire B^4 with the ground between the office and the guarded structure, and might happen to introduce a resistance so nearly approximating that of the guarded structure that the effect upon the electro-magnets D would be insufficient to cause the electro-magnets either to release the armature D' or to attract the armature D², and yet it would cause a deflection of the galvanometer-needle far enough for it to establish the short circuit, cut out resistance, and enable the electro-magnets to attract the armature D² and sound an alarm.

It will be remembered that during the day, while the inmates of the guarded structure desire to use the doors and windows, the switch I I' is shifted so that its arm I will impinge against the contact-piece c^2 . This causes the shifting of the armature of the electro-magnet K, so that it will impinge against the contact-piece g^1 . Then the electric current passes from the arm I of the switch along the wires B^{22} , B^{13} , and B^{14} ; thence through the coils of the electro-

magnets K, along the wire B^{15} , the key L, and the wires B^{16} , B^{17} , B^{18} , and B^{19} , to the armature of the said electro-magnets, to the contact-piece g^1 , and thence along the wire B^{20} to the earth-plate C. Should the wire B^{13} of the partition then be ruptured and the electric circuit thereby broken, the armature D' of the electro-magnets D would be retracted, thereby effecting the sounding of an alarm. The wire could then be repaired before the inmates of the structure leave it.

The object of providing the arm I of the switch I I' with the tappet I³ is to cause the switch to hold the armature of the electro-magnets K against the contact-piece g^1 whenever the switch is adjusted for the day—or, in other words, with its arm I against the contact-piece c^2 . This is advantageous, because it enables the watchman at the office, when he receives a signal that the guarded structure is to be closed, to determine whether the switch I I' has been adjusted from the day-circuit to the night-circuit. There is so little difference between the resistance of the day and night circuits that otherwise the instrument at the office might not indicate sufficient change to enable the watchman to determine with certainty whether or not the switch I I' had been shifted to establish the night-circuit. The signal sent to the watchman that the guarded structure is to be closed is, it will be remembered, made through breaking the circuit by depressing the key L. If the switch I I' is set for the night, the breaking of the circuit in this manner, and the consequent demagnetization of the electro-magnets K, will cause the circuit to pass from the wire B^{19} through the resistance-coil M, and thence along the wire B^{20} to the ground. If the switch I I' were not shifted to establish the night-circuit, the resistance-coil would not be brought into the circuit by the operation of the key L. The effect on the galvanometer in either case would indicate clearly to the watchman whether the switch I I' had been properly adjusted for the night.

It is obvious that by my improvement I provide for ascertaining whether an alarm proceeds from a cause inside or outside the guarded structure.

I desire to remark that in lieu of the electro-magnets D two separate electro-magnets, one having the armature D' and the other having the armature D², may be used.

What I claim as my invention, and desire to secure by Letters Patent, is—

1. In an electric burglar-alarm, the combination of a main circuit extending from an office to a guarded structure, means located at the office for giving an alarm there when a change occurs in the resistance of the circuit at the guarded structure, an electro-magnet and armature at the guarded structure, a main battery which is located at the office, and which is insufficient to cause the electro-magnet to attract its armature, and yet is suffi-

cient to hold it when attracted, and means with which the armature operates to control the passage of the electric current directly from the armature to the ground or through 5 a resistance-coil to the ground, substantially as specified.

2. In an electric burglar-alarm, the combination of a main circuit extending from an office to a guarded structure, an electro-magnet at the office, an armature therefor capable of being held by the electro-magnet against it when this electro-magnet is energized by the electric current of the main battery, an electro-magnet at the guarded structure, which is 15 incapable, when energized from the main battery, of attracting its armature, but which is capable of holding the armature when attracted, and means with which this armature operates to control the passage of the electric current directly from this armature to the ground or through a resistance-coil to the ground, substantially as and for the purpose specified.

3. In an electric burglar-alarm, the combination of a main circuit extending from an office to a guarded structure, a local circuit at the office, provided with means for giving an alarm, an electro-magnet at the office, an armature therefor capable of being held by the 25 electro-magnet against it when this electro-magnet is energized by the main battery, an electro-magnet at the guarded structure, which is incapable, when energized from the main battery, of attracting its armature, but is capable of holding its armature when attracted, and means with which this armature operates to control the passage of the electric current directly from this armature to the ground or through a resistance-coil to the ground, substantially as specified.

4. In an electric burglar-alarm, the combination of a main circuit extending from an office to a guarded structure, devices located at the guarded structure for causing an alarm 45 to be given at the office in case an attempt is made to gain access thereto, a galvanometer at the office, and means with which the galvanometer-needle, when sufficiently deflected, will operate to short-circuit the main circuit at the office and cause the sounding of an alarm at the office, substantially as specified.

5. In an electric burglar-alarm, the combination of a main circuit extending from an office to a guarded structure, an electro-magnet 55 located at the office, and having an armature which it is normally incapable of attracting, a galvanometer, also located at the office, and means with which the galvanometer-needle, when deflected sufficiently, operates to short-circuit the main circuit, and thereby reduce the resistance of the main circuit to such an

extent that the electro-magnet will be able to attract the said armature, substantially as specified.

6. In an electric burglar-alarm, the combination of a main circuit extending from an office to a guarded structure, an electro-magnet located at the office, and having an armature which it is normally incapable of attracting, a local circuit which can be closed by the 65 said armature, and is provided with a device for giving an alarm, a galvanometer, also located at the office, and means with which the galvanometer-needle, when sufficiently deflected, operates to short-circuit the main circuit, 70 and thereby reduce the resistance of the main circuit, so that the electro-magnet can attract the said armature, substantially as specified.

7. In an electric burglar-alarm, the combination of a main circuit extending from an office to a guarded structure, an electro magnet or magnets located in the office, and having armatures, one of which the electro magnet or magnets, when energized from the main battery, can attract, but not the other, while 80 the normal circuit is maintained, a galvanometer, also located at the office, and serving, when sufficiently deflected by a change of resistance, to establish a short circuit and reduce the resistance, so that the electro magnet or magnets 85 can then attract both armatures, an electro-magnet at the guarded structure, incapable of attracting its armature, but capable of holding it when attracted, and means with which this armature operates to control the passage 90 of the electric current directly from this armature to the ground or through a resistance-coil to the ground, the resistance-coil, when introduced into the circuit, serving to so weaken the electro magnet or magnets at the office as to 95 prevent either armature operating in conjunction therewith from being held attracted, substantially as specified.

8. In an electric burglar-alarm, the combination of a main circuit extending from an office to a guarded structure, a resistance device forming a part of the alarm apparatus and located at the guarded structure, means also located at the guarded structure and serving, on the opening of a window or door of the 105 guarded structure, to throw said resistance device into the circuit at the guarded structure, and a device located at an office where watch is kept, and serving to give an alarm when the resistance device is thus thrown into the circuit at the guarded structure, substantially as 110 specified.
